[57] CLAIM

The ornamental design for a food container, as shown and described.

DESCRIPTION

FIG. 1 is a side elevational view of a food container showing my new design. The opposite side view is identical except there is no corner gap in the raised rim of the cover.

FIG. 2 is a left end elevational view thereof. The opposite end view is identical except there is no corner gap in the raised rim of the cover.

FIG. 3 is a top perspective view thereof showing the side opposite that of FIG. 1 and the end shown in FIG. 2.

FIG. 4 is a top perspective view thereof showing the end and side of FIGS. 2 and 1, respectively.

The design is characterized by the closely spaced horizontal lines on the sides and ends of the food container and by the angled corners of the flanged rims of the food container and cover.
